United States Patent Office.

THOMAS S. SPEAKMAN, OF CAMDEN, NEW JERSEY.

Letters Patent No. 77,331, dated April 28, 1868.

PIPE-CO尤PLING FOR RAILROAD-CAR HEATERS.

The Schedule referred to in these Letters Patent and making part of the same.

TO ALL WHOM IT MAY CONCERN:

Be it known that I, THOMAS S. SPEAKMAN, of Camden, Camden county, New Jersey, have invented an Improved Tubular Connection between Railroad-Cars; and I do hereby declare the following to be a full, clear, and exact description of the same.

My invention consists in the combination of a rigid bell-mouthed tube attached to one car, with a flexible self-packing tube attached to an adjoining car, and sliding in the said rigid tube, thus forming a self-coupling joint between the tubes of the different cars of a railway-train, and providing a continuous pipe for the passage of steam or heated or cold air.

In order to enable others skilled in the art to make and apply my invention, I will now proceed to describe its construction and operation, reference being had to the accompanying drawing, which forms a part of this specification, and in which—

Figure 1 is a sectional view of my improved tubular connection between railroad-cars, and

Figure 2 a plan view of the same.

A and A' represent the bumper-beams of two adjacent railroad-cars, and a a the bumpers. To the bumper-beam A' of one car is secured a reservoir or duct, B, of the shape, or approximating to the shape, illustrated in the drawing; and into a tube, b, permanently secured to this reservoir, passes the coupling-pin D, through a link, E, hinged to the bumper-beam A of the other car. To the latter beam is secured a pipe, F, having a funnel-shaped mouth, f, and into this pipe fits snugly, but so as to slide freely, an elastic tube, G, composed of gum-elastic or other equivalent material, which will not be injuriously affected by heat, the tube being properly strengthened by coils of wire, but so as not to destroy its moderate elasticity. This tube G is secured to a tubular projection, p, on the front end of the reservoir or duct D, and from the rear end of the latter projects a pipe, H, communicating with a distributing-reservoir placed beneath the body of one car, while the pipe F communicates with a similar reservoir beneath the other car, every car in the train having a like reservoir, and the tubular communication between the cars being effected in the manner and by the devices described above.

Either heated air or steam may be forced from the engine or tender, or first car of the train, through the several reservoirs and their tubular communications. If heated air be used, the reservoirs may be provided with gratings for the escape of the air into the cars; and during the summer months the pipes and reservoirs may be employed for distributing cold air through the cars.

Many devices have been proposed for facilitating the heating and cooling of railway-cars by forcing heated air or steam or cold air through the entire train. The main difficulty experienced in attaining this result has been the arranging between the cars of efficient tubular connections, which could be coupled and uncoupled with facility, these connections being generally situated outside the bumper-beams, where they are subjected to the greatest strain, and where they are necessarily more sensibly affected by the lateral vibrations of the cars. The tubes, too, have generally been connected by screw-couplings, which demand more or less tedious manipulation when the cars are connected and disconnected.

Moreover, the tubular couplings outside the bumper-beams must, of necessity, be very loose or slack, so that they can accommodate themselves to the movements of the cars; and if steam be used, a condensation takes place in the pendent portions of the coupling, and the condensed water freezes, so as to destroy the communication between the cars.

These serious objections I overcome by arranging the tubular connections centrally, or thereabouts, with the coupling where they will be least affected by the lateral movement of the cars, and by making the tubes of the cars self-coupling, in the manner described above, for the simple introduction of the tube G into the bell-mouthed tube F, suffices to effect the necessary tight joint; and, while the tube G is comparatively rigid, it possesses elasticity enough to accommodate itself to the slight lateral or vertical movement of the cars at this point, and can at the same time slide freely in the tube F.

I do not claim broadly a flexible connecting-pipe attached to one end of a hot-water or air-pipe beneath a railway-car, and having at the opposite end a tube sliding in a pipe upon another car; but

I claim as my invention, and desire to secure by Letters Patent—

1. A pipe, F, having a bell-mouth at one end, arranged beneath a car as described, and adapted for the reception of a flexible tube, G, which communicates with a reservoir beneath another car, and slides in the pipe F, all as set forth.

2. The reservoir B, communicating with the tubes H and G, and having a recess for the reception of a coupling-pin, D, substantially as specified.

In testimony whereof, I have signed my name to this specification in the presence of two subscribing witnesses.

THOMAS S. SPEAKMAN.
